UNITED STATES PATENT OFFICE.

JAMES HUTCHISON, OF NEWARK, NEW JERSEY, ASSIGNOR TO THOMAS POTTER, SONS & CO., OF PHILADELPHIA, PENNSYLVANIA.

DESIGN FOR OIL-CLOTH.

Specification forming part of Design No. 7,616, dated August 4, 1874; application filed July 28, 1874.
[Term of Patent 3½ years.]

CASE H.

To all whom it may concern:

Be it known that I, JAMES HUTCHISON, of Newark, in the county of Essex and State of New Jersey, have invented and produced a new and original Design for an Oil-Cloth; and I do hereby declare the following to be a specification thereof.

The nature of my design is fully shown in the accompanying photographic illustration, which forms a part of this specification.

What I claim as my invention, and desire to secure by Letters Patent of the United States, is—

The design for an oil-cloth, as shown.

JAMES HUTCHISON.
